UNITED STATES PATENT OFFICE.

JULIUS PEGEL, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 12,335, dated June 28, 1881.

Application filed February 7, 1881. Term of patent 3½ years.

To all whom it may concern:

Be it known that I, JULIUS PEGEL, of New York, in the county and State of New York, have invented a new and original Design for 5 Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

A is a figure consisting of a center composed of circular open flowers surrounded by leaves 15 and foliage, among which are found at intervals small circular flowers. The figure A is surrounded by the patterned bands g d b i, containing several sections of different design.

The figure H consists of rose-like flowers surrounded by leaves, and is inclosed by the patterned bands h i b m d.

The figure D consists of a bunch of circular flowers having projecting from it two separate stems bearing flowers and leaves, and is surrounded by the patterned bands k h g.

The figure B consists of a center of circular flowers with leaves and ferns projecting therefrom, and is surrounded by the patterned bands b, k, and a.

30 The figure G consists of a cluster of star-flowers with projecting ferns.

The group C consists of the figure I, a rose and its surrounding leaves; of the figure J, a branch bearing an open rose and rose-buds; and of the figure L, a cluster of circular flowers 35 and their leaves.

The effect of the design is that of separate bouquets or clusters of flowers and foliage surrounded by broad patterned bands.

I claim—

1. The design for carpets, consisting of the figure A, substantially as shown. 40
2. The design for carpets, consisting of the figure B, substantially as shown.
3. The design for carpets, consisting of the figure D, substantially as shown. 45
4. The design for carpets, consisting of the figure H, substantially as shown.
5. The design for carpets, consisting of the figure G, substantially as shown. 50
6. The design for carpets, consisting of group C, containing figures J I L, substantially as shown.
7. The design for carpets, consisting of patterned bands g, d, b, k, h, i, m, and a, substantially as shown. 55
8. The design for carpets, consisting of group C, containing figures J I L, figures A B D G H, and bands g d b k h i m a, substantially as shown.

JULIUS PEGEL.
